UNITED STATES PATENT OFFICE.

MOSES H. EISEMAN, OF CHICAGO, ILLINOIS.

INFLATABLE TOY.

1,216,425.

Specification of Letters Patent. Patented Feb. 20, 1917.

Application filed May 7, 1915. Serial No. 26,548.

To all whom it may concern:

Be it known that I, Moses H. EISEMAN, a citizen of the United States, and a resident of Chicago, county of Cook and State of Illinois, have invented certain new and useful Improvements in Inflatable Toys, of which the following is a specification.

The invention relates to inflatable toys and seeks to provide an improved simple device which can be inexpensively manufactured. The invention consists in the features of improvement hereinafter set forth, illustrated in the accompanying drawing and more particularly pointed out in the appended claim.

In the drawing, Figure 1 is a plan view of the improved toy. Fig. 2 is a section on the line 2—2 of Fig. 1 but showing the toy in deflated condition. Fig. 3 is a view similar to Fig. 2 but with the balloon inflated. Fig. 4 is a view in elevation partially broken away of the modification.

The improved toy comprises a casing of fabric or like inelastic material of oval, egg-shaped or other elongated form and a substantially spherical inflatable balloon within the casing, the balloon being formed of thin elastic rubber and adapted, when inflated, to conform to the outline of the elongated casing. The improvement may be embodied in different forms. That shown in Figs. 1, 2 and 3 comprises a toy foot-ball.

The casing 10 is formed of segmental sections 11 of fabric or like inelastic material of low cost, the sections being stitched together along seams 12 to form a casing of elongated or oblong form. At one point between its ends, the casing is provided with a slit or opening 13, the edges of which are adapted to be connected by a lacing 14 extending through eyelets 15. A flap 16 with in the casing extends across the slit or opening 13 and is stitched to the casing on one side of the opening.

A substantially spherical balloon 17 of

thin rubber is arranged within the casing and is provided with an inflating nipple 18. Preferably, the body 17 of the balloon and the nipple 18 are integral and seamless, the body of the balloon being substantially spherical. The balloon is also preferably supported within the casing 17 by passing the nipple 18 through an opening of the flap 16. The balloon 17 is formed of thin elastic rubber so that, when it is inflated as shown in Fig. 3, it will distend the elongated oblong casing and conform to the outline thereof. When the balloon is inflated, the nipple 18 can be tied, as indicated at 19 of Fig. 3, and after the nipple is tucked within the slit or opening 13, the edges of the latter can be drawn together by the lacing 14.

If desired, the elongated or oblong casing may be smaller at one end than at the other, as indicated at Fig. 4 and the toy made to represent an animal by a marking or otherwise providing the smaller end of the casing with features and by stitching ears 20, legs 21 and a tail 22 to the casing.

The invention thus provides a simple inexpensive toy which may be of different elongated or oval forms and which can be inflated or distended by a balloon of thin rubber and of ordinary form.

It is obvious that changes may be made without departure from the essentials of the invention as defined in the claim.

I claim as my invention:—

A toy comprising an elongated oblong casing formed of fabric or like flexible, inelastic material, and a substantially spherical inflatable balloon supported within said casing, said balloon being formed of thin rubber and adapted, when inflated, to distend said oblong casing and conform to the elongated shape thereof, substantially as described.

MOSES H. EISEMAN.
